UNITED STATES PATENT OFFICE.

JOHANN OFFERMANN AND THEODOR JEGLER, OF MUNICH, BAVARIA,
GERMANY.

METHOD OF PRODUCING COMPOUND FELTED AND TEXTILE FABRICS.

SPECIFICATION forming part of Letters Patent No. 288,726, dated November 20, 1883.

Application filed January 27, 1883. (Model.)

To all whom it may concern:

Be it known that we, JOHANN OFFERMANN and THEODOR JEGLER, both of the city of Munich, Kingdom of Bavaria, German Empire, have invented certain new and useful Improvements in Methods of Producing Compound Felted and Textile Fabrics, of which the following is a specification.

This invention has reference to an improved method of combining a layer or layers of woven, knit, or other textile fabrics with a layer of felt mechanically, and without the employment of adhesive substances, in such a manner that both fabrics are united into one integral whole. The method may also be used for uniting intimately two uniform or different textile fabrics without any felting, the degree of union being dependent upon the length of time for which the fabrics are exposed to the fulling.

The invention consists of a method for uniting textile fabrics either with a layer of felt or with each other by first subjecting the textile fabric to the action of steam of suitable pressure, then bringing them in contact with the layer of felt, and then passing the fabrics between pressing and fulling rolls until the proper interfelting of the fabrics has taken place.

It consists, further, of textile fabrics in which the warp-threads of one fabric cross those of the other fabric, united thereto at an angle of forty-five degrees, whereby the combined fabric has diagonally-intersecting threads, and consequently increased strength and durability.

To illustrate our improved method of combining textile fabrics with each other or with a layer of felt, the accompanying drawings show, in Figure 1, a diagram that represents the means by which successive steps of our improved method are accomplished, while Fig. 2 represents a textile fabric in which the warp-threads of the fabrics intersect each other in a diagonal direction.

In carrying out our invention the textile fabric which is to be united with felt is first exposed either in short pieces or in continuous lengths of from twenty to fifty yards to the action of steam of any suitable pressure.

This has the twofold purpose, first, to moisten the fabric sufficiently for the following operations; and, secondly, to impart to the fine fibers on the surface of the fabric an erect position, so that they can be more intimately united with the fibers of the felt. The surface of the textile fabrics employed is preferably carded for this purpose, so that the adhesion of the layer of felt is augmented. After the textile fabric has been exposed to the action of steam, it is wound upon a roll, A, while the felt to be united thereto is placed upon a second roll, B. Both layers are passed between two pressure-rolls, C C', and thereby pressed firmly together. The layers are then passed through a bath in which good neutral or alkaline soap, from one to four pounds, more or less, has been dissolved in about twenty-five gallons of water. This solution is placed in an open vessel, D, within which are located the guide-rolls a a a. The surplus solution taken up by the layers is removed by the rolls E E', which are arranged near the opposite end of the vessel D, the layers being then conducted to the drawing-rolls F F'. When the entire length of the layers to be united has been passed through the solution in the vessel D and through the pressure-rolls E E', the extreme ends of the same are united by basting, and then passed continuously, from one to four hours, through between the fulling-rolls F F' and over the guide-rolls b b, whereby an intimate union of the fabric with the felt takes place. The compound fabric thus obtained is then worked up by a common fulling-mill, and washed and stretched on frames, and finally finished and dried as required.

The compound fabric can also be produced, but with less advantage, on a wadding-frame or on a cross-frame of any well-known construction. For this purpose the woolen felt is conducted from the carding-machine on an endless apron, and the carding-machine stopped when sufficient material has been accumulated on the apron. The fabric is then placed on the fleece. If a cross-frame is employed, one of the two crossed felts is replaced by the textile fabric and the same crossed with the felt-fleece. In both cases the compound fabric is finally completed by interfelting, full-.

ing, and finishing. All compound fabrics produced in this manner show as their characteristic features a textile fabric on one side and felt on the other side, so that they retain all 5 the features of textile fabrics, while the felt serves to increase or re-enforce the thickness and body of the same.

The main feature of the method described consists in the fact that the union of the felt 10 with the textile fabric takes place without any adhesive substance, and simply for the reason that the fine fibers which project from the surface of the textile fabrics are interlocked with the fibers of the felt in so intimate a manner 15 that they can only be separated by the use of considerable force. When looser-woven, knit, or other fabrics are united with felt, they are finally so intimately connected therewith that the fibers of the felt penetrate through the 20 textile fabric, so that a compound fabric results, which unites the properties of woven fabrics and of felt.

The compound fabric may also be made of two layers of fabric and an intermediate layer 25 of felt, in which case the layer of felt forms the intermediate or uniting link.

It is not absolutely necessary to employ felt 30 of pure wool, as all felts which are now manufactured, and which consist of a mixture of wool with vegetable or animal fibers of less value, can be employed.

By the method described it is also possible 35 to unite woven fabrics, whether smooth or made in certain patterns, directly and without the use of adhesive substances, as the projecting fibers of the same unite themselves thereby so intimately that the separation of the same cannot take place.

It is a well-known fact that all textile fabrics, 40 in most cases, tear in the direction of the warp or weft threads, but not in a diagonal direction. This fact can be made use of in uniting two layers of textile fabrics and obtaining thereby a compound fabric which cannot be 45 torn in any direction, whereby greater durability of the garments made therefrom is the result. For this purpose the two textile fabrics, as shown in the diagram in Fig. 2, are united by felting them together in such a manner 50 that the warp-threads of one fabric intersect the warp-threads of the other fabric at an angle of about forty-five degrees, so that the compound fabric obtained thereby shows diagonally intercrossing threads in all directions,

and has thereby greater resistance against wear 55 and tear.

It is obvious that a compound fabric formed of two diagonally-intersecting layers which are directly felted together may at either side thereof be furthermore re-enforced by a layer 60 of felt, which is united therewith in the same manner and at the same operation.

Having thus described our invention, we claim as new and desire to secure by Letters Patent—

1. A compound fabric consisting of a layer 70 of woven fabric composed wholly or in part of feltable material and a layer of felted fabric, said layers being felted together, substantially as described.

2. A fabric consisting of two or more woven layers composed wholly or in part of feltable material, said layers being united by interfelting of their adjacent surfaces, substantially as described.

3. A compound fabric consisting of two or more woven layers, each layer being composed wholly or in part of feltable material, the surface fibers of said layers being united by interfelting of their adjacent surfaces, the 80 warp-threads of one layer crossing the warp-threads of the adjacent layer, substantially as described.

4. The method of producing a compound fabric, which consists in first subjecting a sheet 85 of woven fabric composed wholly or in part of feltable material to the action of steam, then pressing a sheet of felted fabric in contact therewith, and then subjecting the said sheets to a fulling operation, substantially as de- 90 scribed.

5. The method of producing a compound fabric, which consists in first subjecting two 95 or more sheets of woven fabric composed wholly or in part of feltable material to the action of steam, then pressing said sheets together, and then subjecting the united sheets to a fulling operation, substantially as described.

In testimony that we claim the foregoing as 100 our invention we have signed our names in presence of two subscribing witnesses.

JOHANN OFFERMANN.
THEODOR JEGLER.
